UNITED STATES PATENT OFFICE.

JOHN W. LARMORE, OF HARRISON, OHIO.

IMPROVEMENT IN FIELD-FENCES.

Specification forming part of Letters Patent No. 56,766, dated July 31, 1866.

To all whom it may concern:

Be it known that I, JOHN W. LARMORE, of Harrison, Hamilton county, Ohio, have invented a new and useful Field-Fence; and I do hereby declare the following to be a full, clear, and exact description thereof, reference being had to the accompanying drawings, making part of this specification.

The object of this invention is a cheap, quickly-erected, and durable field-fence that will shade and occupy as little ground as possible, will afford no harbor for vermin, and which is better braced than, and not so invisible as, the ordinary wire fence.

Figure 1 is a perspective view of two eight-foot panels of my fence. Fig. 2 is an axial section through one of my posts. Fig. 3 shows a modification of my post.

A is a post of malleable or wrought iron, made tapering from base to summit, and provided with round tenons B C at bottom and top, respectively.

Projecting laterally and upward from the side of the post is a vertical series of clips or ears, D, whose distance from the side of the post is such as to receive a wire, E, of suitable thickness. These clips are made thin enough to be capable of being clinched over toward the side of the post, so as to secure the wire simply and effectually by that means.

Two rows of clips may be provided on diametrically-opposite sides of the post, and the clips in the respective rows may alternate in height, as in Figs. 1 and 2, or may correspond in height, as in Fig. 3.

The lower tenon, B, is driven forcibly into a circular drill-hole in a stone base, F, which base may be a rough slab of rock, such as may be found in great abundance in most lime and sand stone districts.

The upper tenon, C, enters an auger-hole in a sixteen-foot rider or scantling, G. The ends of the scantling are gained, g, so as to form a half-lap with the scantlings next in order.

The posts may be forged solid, of X form, out of wrought-iron, or may be cast or drawn into the hollow tapering form of the present

illustration, and rendered malleable in the usual way.

It is believed that this fence combines the desiderata of a field-fence more perfectly than any heretofore devised. It is very quickly put up. The bases and riders may be prepared on slack and rainy days, and the wires, being simply laid in the clips, are secured by bending the tips of the latter toward the side of the post by the tap of a hammer or otherwise. Should a clip be broken off on one side, the post is still available upon the other side.

The fence affords no harbor for vermin, and if occasionally coated with tar or paint may be made to last indefinitely.

The wires being simply laid in the clips and secured by clinching, the latter are not kinked or rendered unavailable in resetting, and are easily and quickly removed by opening the clips should it be desired to shift the fence or to lay the posts over to avoid the devastations of a freshet.

The wooden rider has, in connection with a fence of this class, several important uses. It affords a plain demarkation or obstacle to horses and other stock, which, in play or sudden fright, frequently injure themselves by running violently against the wires. It also acts to brace the fence, and affords a means of crossing the fence without injuring the wires.

I claim herein as new and of my invention—

1. The metallic post A, having the vertical series of flexible ears or clips D to receive and secure the wires in the manner described.

2. A field-fence composed of the following elements, to wit: a metallic post, A, having a bottom tenon, B, to enter a stone foot or base, F, and a top tenon, C, to enter a wooden rider, G, and having a series of ears or clips, D, for the reception of suitable wires E.

In testimony of which invention I hereunto set my hand.

JOHN W. LARMORE.
